FIG 5

FIGURE 1 is a front elevational view of the document reading machine embodying my new design;

FIGURE 2 is a top plan view thereof;

FIGURE 3 is a rear elevational view thereof;

FIGURE 4 is a left side elevational view thereof; and

FIGURE 5 is a right side elevational view thereof.

The views are shaded to indicate areas of contrast.

I claim:

The ornamental design for a document reading machine, substantially as shown and described.
